UNITED STATES PATENT OFFICE.

ISIDOR STERN, OF NEWARK, NEW JERSEY.

DESIGN FOR A COMBINATION GEM AND SETTING.

Application filed October 6, 1926. Serial No. 19,257. Term of patent 7 years.

To all whom it may concern:

Be it known that I, ISIDOR STERN, a citizen of the United States, and a resident of Newark, in the county of Essex and State of New Jersey, have invented a new, original, and ornamental Design for Combination Gem and Setting, of which the following is a specification, reference being had to the accompanying drawing, forming part thereof.

Figure 1 is a top plan view of a combination gem and setting, showing my new design, and

Figure 2 is a side elevation of the setting.

I claim:

The ornamental design for a combination gem and setting, as shown.

ISIDOR STERN.
